(57) **CLAIM**

The ornamental design for a display stand as shown and described.

DESCRIPTION

FIG. 1 is a perspective view from a left side of a display stand, showing a first embodiment of our new design;

FIG. 2 is a perspective view from a right side of the display stand shown in FIG. 1;

FIG. 3 is a further perspective view of the display stand shown in FIG. 1;

FIG. 4 is a further perspective view of the display stand shown in FIG. 2;

FIG. 5 is a top plan view of the display stand shown in FIG. 1;

FIG. 6 is a bottom plan view of the display stand shown in FIG. 1;

FIG. 7 is a left side view of the display stand shown in FIG. 1;

FIG. 8 is a right side view of the display stand shown in FIG. 4;

FIG. 9 is a front view of the display stand shown in FIGS. 3 and 4;

FIG. 10 is a rear view of the display stand shown in FIG. 1; FIG. 11 is an exploded view of the display stand shown in FIG. 1;

FIG. 12 is a perspective view from a left side of a display stand, showing a second embodiment of our new design; FIG. 13 is a perspective view from a right side of the display stand shown in FIG. 12;

FIG. 14 is a further perspective view of the display stand shown in FIG. 12;

(Continued)

FIG. 15 is a further perspective view of the display stand shown in FIG. 13;
 FIG. 16 is a top plan view of the display stand shown in FIG. 12;
 FIG. 17 is a bottom plan view of the display stand shown in FIG. 12;
 FIG. 18 is a left side view of the display stand shown in FIG. 12;
 FIG. 19 is a right side view of the display stand shown in FIGS. 14 and 15;
 FIG. 20 is a front view of the display stand shown in FIGS. 14 and 15;
 FIG. 21 is a rear view of the display stand shown in FIG. 12; and,
 FIG. 22 is an exploded view of the display stand shown in FIG. 12.
 The broken lines depict portions of the display stand that form no part of the claimed design.
